GOGGLE

Agaton Aris Balanon, Kalaheo Kauai, Territory
of Hawaii

Application April 17, 1943, Serial No. 483,385

1 Claim. (Cl. 2-14)

This invention relates to goggles.

An object of this invention is to provide goggles which may be used for diving or for other purposes and which can be made by hand with a pocket knife from wood or the like material.

A further object of this invention is to provide a device of the character described in which a number of the frames may be made from a long stick of wood, the goggle being so shaped as to fit closely around the eyes of the wearer and each pair of goggles being interconnected by a link to permit each goggle to move into position to fit the face of the wearer without being hampered by the other goggle.

Yet a further object of this invention is to provide a compact, durable pair of goggles which shall be relatively inexpensive to manufacture, attractive in appearance and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claim.

Fig. 1 is a front, elevational view of a pair of goggles embodying the invention;

Fig. 2 is a cross-sectional view taken on line 2-2 of Fig. 1;

Fig. 3 is a rear, elevational view of one of the goggles; and

Fig. 4 is a partial, elevational view of a stick of wood from which a plurality of goggle frames may be cut.

Referring now in detail to the drawing, 10 designates a pair of goggles. Each goggle 11 comprises a frame 12 and a pane or window 13. The frame 12 may be made of wood or any other suitable material. It has a flat front surface 14 formed with an annular recess or groove 15 and with a through opening 16 connecting with said groove. The side surface 17 of the frame 12 extends at an angle to the front surface 14. The rear surface 18 of the frame is grooved rearwardly and downwardly so as to fit the surface of the face around the eye. Said rear surface 18 is furthermore inclined forwardly and downwardly so as to form an edge 18a adapted to contact the face. The edge portion engaging the face tends to make the goggles more or less waterproof. Notches 21 are cut on opposite sides of

the outer edges of the goggles to form a central wall 22. The wall 22 is formed with a through opening 23 to receive a string 24 for attaching the goggles around the head of the wearer. The window or glass 13 may be fixed within the bottom of the groove 15 by plastic wedge 25. The entire frame may be shellacked or otherwise coated or finished.

Screwed to the inner side of each frame 12 is an eye 26. The eyes 26 of the two goggle frames are interconnected by a link 27.

The goggle frames may be made from a long stick of wood 30. The stick is planned longitudinally and then cut transversely along inclined planes 31 to form pieces 32 from which the goggle frames are made. The pieces 32 are then cut along the lines 33 to form the rear surface of a goggle frame. It will be noted that the goggle frames can be cut by means of a pocket knife. 15 The through opening 16 of each goggle frame preferably converges toward the rear as shown in Fig. 2 of the drawing.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

A solid wooden goggle frame of substantial and non-uniform thickness comprising a front flat surface and having a through opening, said front surface having an annular groove, a window seated in said groove, means holding said window in its grooved seat, said frame further having a rear surface grooved rearwardly and downwardly, said rear surface being inclined forwardly and downwardly forming an edge to fit the face of the user around the eye, said through opening converging towards the rear of the frame, said frame having notches on the opposite sides of the outer edges thereof forming a wall, said wall having an aperture, and a string in said aperture for attaching the goggle frame around the head of a wearer.

AGATON ARIS BALANON.
